ANODE INSULATING STRUCTURE

Ward W. Watrous, Jr., Chatham, N. J., assignor
to Chatham Electronics Corporation, Newark,
N. J., a corporation of New Jersey

Application December 29, 1950, Serial No. 203,439

5 Claims. (Cl. 313—199)

1

This invention relates to anode insulators as applied to gaseous discharge devices, and has particular reference to the structural mounting of anodes used in high voltage two and three element tubes.

The anode mounting of a gaseous discharge device has always been a problem in the design and operation of gas tubes at high voltage. Efficient high voltage rectifiers usually employ a shield which encloses the anode as completely as possible. Three electrode gaseous tubes also enclose the anode in a shield which is generally connected to the control electrode to insure adequate control of the cathode-anode current and eliminate conduction in the tube when the anode is at a negative potential.

However, the anode lead must be brought out of the enclosing shield and envelope for electrical conduction; hence, the shield or the control electrode structure cannot completely surround the anode and there is always the possibility that a non-controllable glow discharge may be started between the anode lead-in conductor and the other electrodes or shield. Such a glow discharge generally starts over a comparatively long path where ionization by collision is effected. The limitations of such a construction result in the use of an anode voltage of 10,000 volts or less.

During recent years the desire for higher voltage discharge devices has called for new designs and new systems. The anode structure herein-after described withstands 40,000 volts between the anode and the combined cathode and control electrode. This discharge device operates at a peak current value of 2,500 amperes.

One of the objects of the invention is to provide an improved anode insulating structure which avoids one or more of the disadvantages and limitations of prior art arrangements.

Another object of the invention is to provide an improved insulating structure which can be operated at much higher anode voltages than heretofore.

Another object of the invention is to provide an anode structure which can be assembled easily and without additional construction costs.

Another object of the invention is to insure that no glow discharge will occur outside the normal cathode-anode path.

Still another object of the invention is to permit the use of mechanically strong parts and to facilitate the adequate support of a heavy control electrode structure.

The invention comprises an anode insulating structure for mounting an anode in a gaseous discharge device and includes a lead-in conductor for the anode, a cylindrical conducting guard

2

secured to the anode and surrounding the lead-in conductor, and an inner cylindrical insulator surrounding the conducting guard. On the outside of the inner cylinder, which is usually made of glass, another insulating cylinder is mounted, and it is to this outer cylinder that the enclosing shield is secured.

For a better understanding of the present invention, together with other and further objects 10 thereof, reference is made to the following description taken in connection with the accompanying drawings.

Fig. 1 is a cross sectional view of one form of the anode insulating mounting.

Fig. 2 is a cross sectional view of another form of the anode insulating structure.

Fig. 3 is a cross sectional view of a third variation of the anode insulator.

Fig. 4 is a cross section taken along line 4—4 20 of Fig. 1.

Referring now to Fig. 1, an envelope 10 encloses the evacuated chamber and the electrodes. At the anode and a re-entrant portion 11 of the envelope is employed to seal an outer cylindrical insulator 12 which, in turn, holds an anode lead-in conductor 13 by means of seal 14 at its upper end. An inner cylindrical insulator 15 is also anchored at the anode seal 14 and extends in axial alignment into the tube closely spaced 30 from the outer cylinder.

At the lower end of lead-in conductor 13 a flat plate anode 16 is securely mounted. The lower face of this electrode furnishes the conducting surface for the electrical discharge when the tube 35 is operated. A control electrode 20 and a baffle 21 are mounted below the anode, both being made of metallic conducting material. An enclosing structure surrounds the greater portion of the anode and includes a cylindrical portion 22, a flat disk 23 mounted above the anode 16, and a grid plate 20 below the anode. To secure the shield 40 and keep it always in alignment a clamping arrangement 24 is used to clamp the top portion of the shield to the outside surface of insulating cylinder 12. This clamping feature is made possible by the more rugged construction of this type 45 of structure.

Inside the inner cylinder 15 a conducting cylindrical shell 25 is mounted in close proximity to the inner cylinder. The conducting shell is secured to the anode 16 and acts as a guard to reduce the voltage gradient so that the interior volume surrounding the conductor 13 is field free and, therefore, there is no tendency for an arc or brush discharge to occur at the junction of the support rod 13 and the glass bead.

The spacing between the shell 25 and the inner

insulator 15 is made as small as is convenient for the fabrication processes used. The spacing between the inner insulator 15 and the outer insulator 12 is also made quite small, usually about .030 inch to cut down on the possibility of glow discharges.

These gaseous discharge devices are filled with hydrogen gas at a pressure range from 400 to 900 microns (of mercury) and, therefore, the ions have a mean free path of about one inch and the electrons have a mean free path of about six inches. At low voltages glow discharges should not be expected at distances shorter than half this distance but at 40,000 volts stray collisions may set up a discharge at one tenth the mean free path. For this reason all ionizable paths are kept as short as possible.

The anode insulating structure shown in Fig. 2 is for smaller tubes and lower voltages. It differs from the structure of Fig. 1 in that three cylindrical insulators are used instead of two and there is no static shield. The device has an anode 16, an inner cylindrical insulator 15, an outer cylindrical insulator 12, and an intermediate insulator 30. The shield 23 is secured to the outer insulator in the usual manner.

The design shown in Fig. 3 is similar to that of Fig. 1 except that the outer insulating cylinder is limited in length and extends only from the upper shield disk 23 to the seal between the re-entrant portion of the envelope 11 and the inner cylinder 15. In this manner the length of path between cylinders is shortened and the chances of an uncontrolled glow discharge are greatly reduced. The design shown in Fig. 3 also differs from Fig. 1 in the arrangement of the lead-in seal and the outer rim of the re-entrant portion. The shield 25, inner cylindrical insulator 15, and seal 14 are lowered so that an insulating substance 18, such as wax, silicone jelly, or other satisfactory insulating compound, may be employed to fill the re-entrant cavity and completely cover the junction between the bead 17 and the lead-in insulator 13.

When the discharge device is in operation, there is a strong electric field between conducting shield 25 and the clamping structure 24. Most of the lines of force in this field are normal to the surfaces of the shield and the clamp, but in the vicinity of the shield plate 23 the electric field is concentrated at the position 31 where the shield plate is positioned nearest to the shield. Because of this concentration the lower end 32 of insulating cylinder 12 is in an electric field which is comparatively weak and there is little or no tendency at this point to effect sparking due to the junction of an insulator and a conductor. The lower end of insulating cylinder is in a strong electric field but touches no metal at or near this point.

From the above description it will be evident that the invention provides an anode structure which is sturdy, capable of withstanding high voltage, and efficient in radiating heat losses.

While there have been described and illustrated specific embodiments of the invention, it will be obvious that various changes and modifications may be made therein without departing from the field of the invention which should be limited only by the scope of the appended claims.

I claim:

1. An anode insulating structure for mounting an anode in a gaseous discharge device comprising, a lead-in conductor for the anode, a cylindrical conducting guard secured to the anode and

surrounding the lead-in conductor, an inner cylindrical insulator surrounding the conducting guard, an outer cylindrical insulator surrounding the inner cylindrical insulator, and mounting means for securing an electrode on the outer cylindrical insulator.

2. An anode insulating structure for mounting an anode in a gaseous discharge device comprising, an anode lead-in conductor sealed in a glass envelope for supporting the anode, a cylindrical conducting guard secured to the anode and surrounding the lead-in conductor, an inner cylindrical insulator surrounding the conducting guard, an outer cylindrical insulator surrounding the inner cylindrical insulator, and clamping means on the outer cylindrical insulator for securing a low voltage metallic shield.

3. An anode insulating structure for mounting and insulating the anode in a gaseous discharge device comprising, an anode lead-in conductor sealed in a glass envelope for supporting the anode, a cylindrical conducting guard secured to the anode and surrounding the lead-in conductor, an inner cylindrical glass insulator secured to the glass envelope and surrounding the conducting guard, an outer cylindrical glass insulator also secured to the glass envelope and surrounding the inner cylindrical insulator, and clamping means on the outer cylindrical insulator for securing a low voltage metallic shield.

4. An anode insulating structure for mounting a high voltage anode of a gaseous discharge device comprising, an anode lead-in conductor sealed in a glass envelope for supporting the anode and providing an electrical connection to an external source of power, a cylindrical conducting guard secured to the anode and surrounding the lead-in conductor, an inner cylindrical glass insulator secured to the glass envelope and surrounding the cylindrical conducting guard in close proximity thereto, an outer cylindrical glass insulator also secured to the glass envelope and surrounding the inner cylindrical insulator in close proximity thereto, and clamping means on the outer cylindrical insulator for securing a low voltage metallic shield.

5. An anode insulating structure for mounting a high voltage anode of a gaseous discharge device comprising, an anode lead-in conductor sealed in a glass envelope for supporting the anode and providing an electrical connection to an external source of power, a cylindrical conducting guard secured to the anode and surrounding the lead-in conductor, an inner cylindrical glass insulator secured to the glass envelope and surrounding the cylindrical conducting guard with a spacing from said guard of less than one-tenth of the mean free path of the gas within the discharge device, an outer cylindrical glass insulator also secured to the glass envelope and surrounding the inner cylindrical insulator with a spacing from said inner insulator of less than one-tenth of the mean free path of the gas, and clamping means on the outer cylindrical insulator for securing a low voltage metallic shield.
